(57) **CLAIM**

The ornamental design for a binoculars, as shown and described.

DESCRIPTION

FIG. 1 is a perspective view of binoculars of the present invention;

FIG. 2 is a front elevational view of the binoculars of the FIG. 1;

FIG. 3 is a rear elevational view of the binoculars of FIG. 1;

FIG. 4 is a top plan view of the binoculars of FIG. 1;

FIG. 5 is a bottom plan view of the binoculars of FIG. 1;

FIG. 6 is a right side view of the binoculars of FIG. 1;

FIG. 7 is a left side view of the binoculars of FIG. 1;

FIG. 8 is a perspective view of a second embodiment of binoculars of the present invention;

FIG. 9 is a front elevational view of the binoculars of the FIG. 8;

FIG. 10 is a rear elevational view of the binoculars of FIG. 8;

FIG. 11 is a top plan view of the binoculars of FIG. 8;

FIG. 12 is a bottom plan view of the binoculars of FIG. 8;

FIG. 13 is a right side view of the binoculars of FIG. 8; and, FIG. 14 is a left side view of the binoculars of FIG. 8.

The broken line(s) immediately adjacent the shaded areas represent the bounds of the claimed design while all other broken lines are directed to environment and are for illustrative purposes only, the broken lines form no part of the claimed design.
